UNITED STATES PATENT OFFICE.

BEN WILLARD, OF NEW ORLEANS, LOUISIANA, ASSIGNOR TO GENERAL ELECTRIC COMPANY, A CORPORATION OF NEW YORK.

BRANDING DEVICE.

Application filed March 23, 1927. Serial No. 177,692.

My invention relates to branding devices and has for its object the provision of a simple and reliable device of this character in which provision is made for heating a plurality of different branding irons.

More particularly my invention relates to branding irons suitable for marking wood and various other materials such, for example, as may be used in the grading and marking of lumber. In this process it is necessary to have a plurality of irons having different brands available so as to apply the various grade marks.

In carrying out my invention I provide a heat insulated casing in which a plurality of electrically heated branding irons may be placed when not in use together with means for establishing an electric heating circuit for each iron when it is placed in the casing so that the iron is maintained at the proper temperature. I also provide an extension cord connected to the supply circuit to which the iron may be connected when removed from the casing and thereby maintained at the proper temperature while in use.

For a more complete understanding of my invention reference should be had to the accompanying drawing in which Fig. 1 is a front elevation view partly in section of electric branding means embodying my invention; Fig. 2 is an end elevation view of Fig. 1 partly in section; while Fig. 3 is a diagrammatic view showing the electrical connections for an iron.

Referring to the drawing, I have shown my invention in one form in connection with branding irons such as are suitable in the grade marking of lumber. A plurality of irons 10 are provided which are identical in construction, but with the exception that each iron is provided with a different brand. In other words, a separate iron will be provided for each grade mark to be burned into the lumber. It is desired, however, that the irons will be maintained ready for instant use and to this end I provide a casing or cabinet 11 in which the irons are placed in upright positions, the cabinet being provided with a front door 12 which may be opened to provide for the insertion and removal of the irons. In the top of the casing is a plurality of separate compartments 13 which are surrounded by heat insulated side and top walls 14. Each compartment is of sufficient size to receive the heated end portion 15

of the branding iron, the brand design being carried on the upper end of the portion 15. This heated portion is secured to a rod 16 which terminates in a suitable handle 17.

Each iron is provided with a suitable electric heating resistor 18 in the portion 15 together with a thermostat control device 19 by means of which the circuit of the heater 18 is controlled so as to maintain the iron at a predetermined temperature. In the arrangement shown the thermostat opens and closes the circuit for a magnet coil 20 located in a bottom compartment 21 in the cabinet. This coil operates a suitable switch 22 in circuit with the resistor 18 whereby the switch 70 is opened when the coil is energized by the closing of the circuit by the thermostat upon the occurrence of a predetermined temperature. As the branding iron cools, it will be understood that the thermostat will 75 operate at some predetermined minimum temperature to open the circuit for the coil 20 whereby the switch 22 is closed by the spring 23 to reestablish the heating circuit. As previously observed the magnet coil 20 80 and the switch 22 associated with each branding iron are mounted in the lower compartment 21. The conductors 24 and 25 leading to the resistor and the conductor 26 for the thermostat control circuit extend through the 85 rod 16 and the handle 17 and terminate in the contact pins 27 at the end of the handle.

In the bottom wall 28 of the cabinet is mounted a plurality of contact receptacles 29, each receptacle being directly below a compartment 13 and having three socket contacts to receive the contact pins 27 whereby the circuit connections with a supply source 30 of suitable voltage shown in Fig. 3 are established. Preferably the conductor 26 95 for the thermostat is connected to the middle one of the contact pins 27 so that the proper circuit relations will be established in all cases.

Each iron when not in use is placed in the casing in a proper upright position to establish its heating circuit whereby it is maintained under the thermostat control at the proper temperature. The loss of heat when the irons are in the casing is reduced to a minimum by means of the heat insulating walls 14 surrounding the heated portions of the branding irons. When the iron is removed from the casing for use its connections with the heating circuit may be re- 110

established and maintained through an extension cord 31 comprising three insulating conductors which terminate in a plug receptacle 32 corresponding to the receptacles 28 in the 5 casing. It will be understood that the extension cord 31 has connection with an operating coil 20 and a switch 22 to establish the connections indicated in Fig. 3.

While I have described my invention as 10 embodied in concrete form and as operating in a specific manner in accordance with the provisions of the patent statutes, it should be understood that I do not limit my invention thereto since various modifications thereof 15 will suggest themselves to those skilled in the art without departing from the spirit of my invention the scope of which is set forth in the annexed claims.

What I claim as new and desire to secure 20 by Letters Patent of the United States is:—

1. The combination with an electrically heated tool, of a casing therefor, means for establishing a heating circuit for said tool when it is placed in said casing, and a thermostatic cut-out for controlling the heating circuit of said tool to maintain a predetermined temperature while said tool is in use.

2. The combination with an electrically heated tool of a casing therefor and means 30 for establishing a heating circuit for said tool concurrently with the placing of said tool within said casing, and a thermostatic cut-out for controlling said heating circuit to maintain a predetermined temperature 35 in said tool.

3. A branding device comprising an electrically heated branding iron, a heat insulated casing therefor, means for establishing a heating circuit for said iron when it is 40 placed in said casing, a thermostatic cut-out on said iron for controlling the heating circuit thereof so as to maintain said iron at a predetermined temperature, and an extension cord provided with means for establishing a heating circuit for said iron when said iron 45 is removed from said casing for use.

4. An electric branding device comprising

a heat insulated casing, an electric contact receptacle in said casing, an electric branding iron in said casing, a handle for said iron, 50 contact pins on said handle cooperating with said receptacle to establish a heating circuit for said iron and a thermostatic cutout on said iron for controlling the heating circuit thereof so as to maintain said iron at 55 a predetermined temperature, said iron being freely removable from said casing whereby its heating circuit is broken.

5. A branding device comprising a heat insulating casing, a plurality of electric contact receptacles on the bottom of said casing, a plurality of electrically heated branding irons in said casing, handles for said irons, contact pins for said irons cooperating with said receptacles to establish an electric heating circuit for said irons, and a thermostatic cutout in each of said irons for controlling the heating circuit thereof so as to maintain said irons at a predetermined temperature, 70 said irons being freely removable separately from said casing, whereby the electric circuit therefor is broken by the removal of the contact pins from said receptacle.

6. A branding device comprising a heat insulated casing, a plurality of electrically 75 heated branding irons provided with handles arranged to be placed in said casing, electric contact receptacles in said casing, contact pins on said irons arranged to cooperate with said receptacles to establish heating circuits 80 for said irons when they are placed in said casing, a thermostatic control device in each of said irons for maintaining said irons at a predetermined temperature, said irons being freely and separately removable from said 85 casing whereby the heating circuits thereof are broken, and an extension cord provided with means for establishing a heating circuit for each of said irons when removed from the casing.

In witness whereof, I have hereunto set my hand this 18th day of March, 1927.

BEN WILLARD.
